US00D635652S

(12) **United States Design Patent**
Andersson

(10) **Patent No.:** **US D635,652 S**
(45) **Date of Patent:** **** Apr. 5, 2011**

(54) **THREE-CIRCUIT HEAT EXCHANGER**

(75) Inventor: **Sven Andersson**, Hassleholm (SE)

(73) Assignee: **Swep International AB**, Landskrona (SE)

(**) Term: **14 Years**

(21) Appl. No.: **29/359,114**

(22) Filed: **Apr. 6, 2010**

(30) **Foreign Application Priority Data**

Oct. 6, 2009 (EM) 001620113

(51) **LOC (9) Cl.** **23-03**

(52) **U.S. Cl.** **D23/323; D23/330**

(57) **CLAIM**

The ornamental design for three-circuit heat exchanger, as shown and described.

DESCRIPTION

FIG. 1 is a top plan view of showing my design thereof;
FIG. 2 is a bottom plan view;
FIG. 3 is a right side elevation view;
FIG. 4 is a left side elevation view;
FIG. 5 is a first end elevation view;
FIG. 6 is a second end elevation view;
FIG. 7 is a front perspective view; and,
FIG. 8 is a rear perspective view of thereof.
